Inventor

LOUIS HAAS.

By his Attorney,
Paul Combel Mellee.

UNITED STATES PATENT OFFICE.

LOUIS HAAS, OF NEW YORK, N. Y.

MUSIC-ROLL CONTAINER.

No. 922,695.

Specification of Letters Patent.

Patented May 25, 1909.

Application filed March 5, 1908. Serial No. 419,279.

To all whom it may concern:

Be it known that I, LOUIS HAAS, a citizen of the United States, residing at New York, county of New York, State of New York, have invented certain new and useful Improvements in Music - Roll Containers, of which the following is a full, clear, and exact description.

My invention relates to improvements in music roll containers, the object of the invention being to provide a proper centering means for the roll and a strengthening and reinforcing device for the container, whereby when the roll is inserted in place and while it is in place, the danger of injury to the box is eliminated.

In the accompanying drawings, Figure 1 is a plan view of a container with the roll in place and cover removed, said view being broken away at the center; Fig. 2 is an end elevation of the container with the cover removed; Fig. 3 is a cross section of the container, including the cover and looking toward one end; Fig. 4 is a longitudinal section taken at one side of a median line and looking toward the centering device, the latter and one end of the roll being shown in elevation.

1 represents a roll of music of well-known form, said roll having pin-like extensions 1^a at each end, by means of which the roll is supported when in use in a suitable music playing instrument.

2 is a box or container, usually made of pasteboard, the dimensions being proper to receive the roll 1.

2^a is a cover, such as is customarily employed, for the box 2.

It is obvious that if no means were provided to prevent end play of the roll within the box, the pins 1^a might puncture the ends of the same and injure it seriously.

The main object of this invention is to provide a simple and effective means for reinforcing the ends of the box 1, so as to properly guide the roll in place when it is being inserted, and so as to hold it in such a manner as to prevent the above injury to the ends of the box. To that end I provide, within the box and at each end thereof, a novel form of guide, centering and reinforcing device comprising, in its preferable form, a main body or plate 3, which furnishes a backing. Projecting forwardly from each edge of this main body 3 are cheek pieces 4—4, the edges of which incline from their lower ends toward

the backing 3, as best seen in Fig. 4. 5 is a supporting shoulder at the bottom of the backing plate 3, formed by turning up the lower end or extremity of said plate. 6—6 are clips at the upper edge of the plate 3 and arranged to be bent over tightly upon the upper edge of the end of the box. The outline of the blank from which this reinforcing device is formed, is such as indicated in dotted lines in Fig. 3. To fasten the reinforcing device in place requires merely the turning over of the ears 6—6, so that they will tightly embrace the material forming the end of the box. The space between the ears 4—4 and 5 is U-shaped when viewed from the inner side (see Fig. 3), and into this U-shaped space the pin end 1^a slides when the roll is inserted, so that said roll will stand approximately as shown in Fig. 1, in which position no amount of jarring or vibration will cause said roll to shift longitudinally in the box so as to puncture the ends.

The plate 3 not only provides an impervious backing to prevent puncture by either pin end 1^a, but it also provides a broad bearing against the inner face of the box end, whereby it will be prevented itself from cutting through or piercing said box end.

What I claim is:

1. In a device of the character described, a box-like container for music rolls, a sheet metal roll centering and reinforcing device comprising a flat plate and a pin support formed therefrom comprising integral sides 90 bent forward from said plate and a bottom support bent forwardly from said plate, the forward edges of the integral side members receding upwardly toward the plate to form a guiding incline, and fastening means whereby said plate may be secured in the container.

2. In a device of the character described, a box-like container for music rolls, a roll centering and end reinforcing device comprising 100 a flat plate, the sides and lower edges being bent forwardly to form a pin-receiving recess, the extreme edges of the forwardly projecting sides receding upwardly toward the plate, and integral fastening devices near the 105 upper edge of said plate whereby the same may be secured to the box end.

3. In a music roll container, a box arranged to receive the roll, a roll centering and end reinforcing device comprising a frame 110 providing a pin-receiving recess open at the top, fastening devices integral with the top

of said frame arranged to secure the same to the box end, said frame including a broad bearing arranged to rest flatwise against the inner wall of the end of the box and constituting an integral backing arranged in line with the axis of a music roll when the latter is in place.

4. In a music roll container, a box arranged to receive the roll, a roll-centering and end-reinforcing device formed of sheet metal and comprising a backing plate having oppositely arranged ears having similarly in-

clined edges, said ears being bent forward to cause said edges to lie in substantially the same plane, a depending ear, said depending ear being bent forwardly to furnish a pin support, an upwardly projecting ear arranged to be bent over to secure said device in place on the end of said container. 15
